MOVABLE LAMP SUPPORT

Filed March 20, 1928

UNITED STATES PATENT OFFICE

NILS G. CARLSON, OF SOUTH BEND, INDIANA

MOVABLE LAMP SUPPORT

Application filed March 20, 1928. Serial No. 263,188.

This invention relates to improvements in a movable lamp support, and has for one of its principal objects, the provision of means for optionally positioning an electric lamp, so as to illuminate a desired portion of a 5 room, workshop, foundry floor or the like.

One of the most important and most difficult problems faced by our present day industrial and manufacturing world is the proper and efficient lighting of its workshops, 10 foundries and the like. This is especially true of a foundry, as the making of the molds is extremely delicate work, and good illumination is imperative. When the work is large, the position of the ordinary lamp supports 15 with respect to the work is fixed, therefore only a portion of the work is illuminated, and inasmuch as the work cannot be moved to permit the rays of the light to fall on another desired portion of the work, the molder must 20 do his work under very trying conditions. In an iron foundry, this need of light is felt the keenest, as the molding sand used is black and good illumination is most essential.

One of the important objects of this invention 25 is to provide a lamp support which is movably mounted on an overhead rail or track and which may be positioned over any portion of a foundry or shop floor, or the like, thereby eliminating the necessity of 30 using a number of lamps to illuminate various portions of a large piece of work, and also rendering every portion of the work visible from any angle.

Another difficulty met with in illuminating 35 shops and foundries is the frequency with which the lamps and their accompanying reflectors must be cleaned. This situation is particularly troublesome in grain mills, cement mills, flour mills, and foundries, and in 40 fact, any place where finely divided particles of solid matter are apt to accumulate upon the lamps and reflectors. This condition necessitates a weekly or even a daily cleaning 45 of the lamps, and with the ordinary fixtures this presents a considerable task, as the lights are usually positioned in such a place that a ladder must be used to reach each individual lamp.

Another important object of this invention

is the provision of means for removing the lamp from its position over the working floor to a portion of the shop which can be used, as in the case of cleaning the lamps, for that purpose. The rails upon which the lamp supports ride can all terminate at a balcony 55 or the like to which each light in its turn may be pulled and there cleaned. It is obvious that the laborious task of going from light to light on the working floor and ascending 60 and descending a ladder at each light is therefore eliminated.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the device, illustrating the movable mounting of the lamp.

Figure 2 is a detail end view of the lamp supporting trolley.

Figure 3 is a sectional view taken on the line 3—3 of Figure 2.

Figure 4 is an entire sectional view taken on the line 4—4 of Figure 3.

Figure 5 is an end view partially in section, 50 of the lead supporting trolley.

As shown in the drawings:

The reference numeral 10 indicates generally an ordinary electric lamp, mounted in the usual socket 12, a reflector 14 being preferably positioned over the lamp to properly distribute the light from the lamp. Electrical connection is made to the lamp 10 by means of one end of a duplex lead 16, the other end of which is connected to some remote source of electric current.

An overhead cable, rail or track 18 runs along the ceiling of the portion of the workshop to be lighted, and supported thereon is a lamp supporting trolley 20. Positioned intermediate the current source and member 20, and supported by the rail 18 is a conductor guide. As best shown in Figure 5, the guide is constructed in two parts, a wire supporting member 22 and a trolley wheel 24. In 193

order to simplify the mounting and removing of the guide from the rail 18 the member 22 is constructed of some resilient metal, such as steel or the like, and bent double upon itself, the ends being inwardly disposed and adapted to form a bearing for the wheel 24. It can readily be seen that to remove the cable guide from the track 18, the juxtaposed ends of the guide 22 need merely be sprung apart.

10 The lamp supporting member 20 comprises two companion portions 26 and 28 fastened together by means of rivets or the like 30. A trolley wheel 32 embraced between the upper ends of the members 26 and 28 is adapted to ride on the rail 18. In order that the element 20 as a whole, may be readily demountable from the rail 18, the trolley wheel 32 can be removed by merely unscrewing a combination bolt and bearing 34.

20 The duplex conductor 16 is drawn from a remote outlet through the guide 22 and through an opening 36 in the body of the support 20. Another opening 38 at the bottom of the support 20 intersects the opening 36 at right angles, and the conductor passes therethrough to the socket 12. If desired, a switch 40 may be interposed in the circuit of the conductor 16, permitting the workman to turn the light off and on at will. This switch extension may also be used as a means for moving the body 20 along the rail.

25 It is apparent that herein is provided a device which is ideally adapted for use in a factory, foundry or mill. Better illumination will result and one lamp used in conjunction with this device will perform the function of several lamps used with the ordinary stationary fixtures.

30 I am aware that many changes may be made and numerous details of construction varied throughout a wide range without departing from the principles of this invention, and I therefore do not purpose limiting the patent granted hereon otherwise than as necessitated by the prior art.

45 I claim as my invention:

A movable lamp support including in combination, a rail, a trolley member movably positioned on the rail, and means for suspending a lamp from the trolley member, said means comprising a pair of juxtaposed elements forming the trolley member, an electric duplex lead, also depending from the trolley member a manually operated depending switch at the end of the duplex lead, the said trolley member having two intersecting openings adapted to house the electric duplex lead, rivets permanently connecting the two elements, one portion of said duplex lead supporting the lamp and the other portion supporting said manually operated switch, said last-named portion also comprising means for manually shifting the lamp along the rail.

55 In testimony whereof I affix my signature.

NILS G. CARLSON.
